see, Germany; vested in the Alien Property Cus-
todian

Application March 15, 1938, Serial No. 195,949
In Germany March 31, 1937.

4 Claims. (Cl. 244—106)

The present invention relates to a new and improved airplane, more particularly to a seaplane in which parts of the wings act as floats and which has no specially projecting floats which increase weight and air resistance.

It is an object of the present invention to provide an airplane of the type specified which has no floats which project from the wings and which are likely to be broken away at rough landings, and which has no floats in the form of stumps projecting from the fuselage on which stumps the forces of buoyancy act on a short lever and cause considerable rocking of the seaplane. The plane according to the present invention also obviates the shortcomings of seaplanes in which the wings are connected to the fuselage at a very low point whereby the root of the wing is supposed to act as a float; also in the latter case the flying boat is subjected to undesirable rocking and it is quite possible that the tips of the wings dip into the water or that, when starting, such a large part of the wings is flooded that rising of the machine from the water is made impossible.

It is an object of the present invention to provide a flying boat of the monoplane type in which the wings are connected with the fuselage or hull high above the water line and are curved downwards until the contact with the surface of the water is established. From the points of contact of the wings with the water the wings again rise in an outward direction so that the front view of the plane supporting surfaces resembles a W.

A flying boat of the configuration set forth has several advantages over flying boats of conventional design. There are no floats which in spite of great air resistance provide only little buoyancy. The entire wing system according to the present invention is used to provide efficient air supporting surfaces and parts thereof produce buoyancy at a large leverage when the machine rests on the water. The wings rise immediately adjacent to the parts acting as floats at such a steep angle that immersion of the wing tips or roots into the water is prevented.

According to the present invention the parts of the wings which contact the water are made particularly water tight and strong to resist waterhammer and may be built as specially strong hollow floats attached underneath the wings or built in the lowermost parts of the wings and provided with transverse walls which subdivide the float into individual watertight compartments. Instead of such specially built tanks

the interior of the lower parts may be filled with air filled bags or other buoyancy creating means.

Another object of the present invention resides in the provision of a seaplane of the type specified in which the parts of the wings which are outside of the parts which contact the water are removable and/or which are provided with retractable landing gears to adapt the flying machines also to landing on hard ground.

Further and other objects of the present invention will be hereinafter set forth in the accompanying specification and claims and shown in the drawing which, by way of illustration, show what I now consider to be a preferred embodiment of my invention.

In the drawing:

Figure 1 is a diagrammatic front view of a flying machine according to the present invention.

Figure 2 is a diagrammatic front view of a flying machine according to the present invention and being provided with retractable landing gears and in which parts of the wings are removable.

Figure 3 is a large scale view of a part of the wing of an airplane according to the present invention.

Figure 4 shows a modification of the part shown in Fig. 3.

Referring more particularly to Fig. 1 of the drawing, 1 represents the fuselage to which the wing parts 2 are connected laterally and at a point which is high above the water level 11. The root part 2 of the wing carries a propelling unit 18 and is curved downwards until it reaches the water level at the point designated by numeral 3. From point or rather edge 3 the tip parts 5 of the wing project upwards and sideways. The front view of a wing according to the present invention has thus substantially the configuration of a V. The lowest part of the wing part 4 which connects the root and the tip part of the wing is built as a float 17. Disconnectable joints 12 and/or 13 may be provided between the float part 4 and the tip part 5 and/or the root part 2 of the wing. When the machine rests on the water for longer periods or when the outer ends of the wings are not needed or when these parts constitute a hindrance it may be found convenient to make use of said disconnectable joints.

Fig. 2 shows a flying machine which is similar to that shown in Fig. 1 and which is provided with a landing gear 6 which is connected to the lowest part 7 of the wing which is constructed as a float 9. The landing gear can be completely

retracted into a suitable cavity 18 which is provided for this purpose in the part 8 of the wing which is the part which is connected to the main body 1. Due to the disconnectable joint 14 the tip parts 5 may be taken off if desired.

Fig. 3 shows a top view of the float and joint part 9, 14. The float part is provided with separating walls 15 whereby a plurality of individual watertight compartments is formed.

In addition or instead of the subdividing walls 15 a plurality of individual watertight bags 16 may be provided as are shown in Fig. 4.

While I believe the above described embodiments of my invention to be preferred embodiments, I wish it to be understood that I do not desire to be limited to the exact details of design and construction shown and described, for obvious modifications will occur to a person skilled in the art.

I claim:

1. A hydroplane comprising a hull, a wing comprising a root portion cantilever like connected to the upper part of said hull and extending laterally downward from the upper part of the hull and having an upper and a lower surface, both surfaces being curved towards said hull, said root portion forming a completely unobstructed cavity extending alongside said hull, a main wing portion having an inner end connected to the outer end of said root portion and having an upper and a lower surface, both said surfaces being concavely curved with respect to the ground and extending laterally upward from the outer end of the respective surfaces of said root portion, the lower surface of the outer end of said root portion and the lower surface of the inner end of said main wing portion merging into a downward pointing edge like portion and forming an acute angle with one another, said edge like portion being substantially as low as the normal water level of said hull and float means disposed entirely inside said wing above said edge like portion.

2. A hydroplane comprising a hull, a wing comprising a root portion cantilever like connected to the upper part of said hull and extending laterally downward from the upper part

of the hull and having an upper and a lower surface, both surfaces being curved towards said hull, said root portion forming a completely unobstructed cavity extending alongside said hull, a main wing portion having an inner end connected to the outer end of said root portion and having an upper and a lower surface, both said surfaces being concavely curved with respect to the ground and extending laterally upward from the outer end of the respective surfaces of said root portion, the lower surface of the outer end of said root portion and the lower surface of the inner end of said main wing portion merging into a downward pointing edge like portion and forming an acute angle with one another, said edge like portion being substantially as low as the normal water level of said hull and float means disposed entirely inside said wing above said edge like portion and extending over the whole length of said edge like portion across the wing.

3. A hydroplane comprising a hull, a sectional wing comprising a root section cantilever like and permanently connected to the upper part of said hull and extending laterally downward from the upper part of the hull and having an upper and a lower surface, both surfaces being curved towards said hull, said root section forming a completely unobstructed cavity extending alongside said hull, an intermediary section removably connected to the outer end of said root section and having an upper surface portion extending trough-like across said wing and having a lower surface composed of two surface portions merging into a downward pointing edge like portion and forming an acute angle with one another, said edge like portion being substantially as low as the normal water level of said hull, and a main wing section removably connected to said intermediary portion and having an upper and a lower surface, both said surfaces being concavely curved with respect to the ground and forming the continuation of the respective outward portions of said intermediary section.

4. A hydroplane as set forth in claim 3 comprising float means disposed entirely inside said intermediary section.

CLAUDE DORNIER.
